J. P. KYLE,
SEAT ATTACHMENT,
APPLICATION FILED OCT. 9, 1917.

1,275,704.

Patented Aug. 13, 1918.

UNITED STATES PATENT OFFICE.

JOHN P. KYLE, OF AREDALE, IOWA.

SEAT ATTACHMENT.

1,275,704.

Specification of Letters Patent. Patented Aug. 13, 1918.

Application filed October 9, 1917. Serial No. 195,588.

To all whom it may concern:

Be it known that I, JOHN P. KYLE, a citizen of the United States, residing at Are-
dale, in the county of Butler and State of
Iowa, have invented certain new and useful
Improvements in Seat Attachments; and I
do hereby declare the following to be a full,
clear, and exact description of the invention,
such as will enable others skilled in the art
10 to which it appertains to make and use the
same.

This invention relates to a new and useful
seat attachment for use in connection with
farming implements and particularly culti-
15 vators.

The principal object of the invention is to
provide a seat attachment of this character
embodying adjustable cushioning means for
the seat to afford ease and comfort to the
20 rider during the travel of the farming ma-
chine over the ground.

A further object of the invention is to pro-
vide reliable and durable seat attachment
of simple and inexpensive construction.

25 With these and other objects in view, the
invention comprises the various novel fea-
tures of construction, combination and ar-
rangement of parts which will be fully de-
scribed hereinafter and afterward specifi-
30 cally claimed.

Referring to the drawing:

Figure 1 represents a plan view of my im-
proved seat attachment,

Fig. 2 represents a side elevation of the
35 attachment, and

Fig. 3 represents a vertical sectional view
taken on a plane indicated by the line 3—3
on Fig. 2.

Similar characters of reference are used
40 to denote like parts throughout the follow-
ing description and the accompanying draw-
ings.

In order that the construction and opera-
tion of the invention may be readily under-
45 stood, I have illustrated an approved em-
bodiment thereof in the accompanying draw-
ings and will now proceed to fully describe
the same in connection with said drawings,
in which 1 indicates a pair of spaced flat
50 bars which converge rearwardly for the
major portion of their length. The forward

ends are each provided with an aperture 2
for the reception of bolts or other suitable
fastening means to secure the attachment to
some convenient intermediate part of the 55
cultivator or other farming machine as the
case may be.

3 designates a pair of angle iron bars
which have their rear ends arranged in
spaced parallel relation and connected by 60
bolts 4. Separator washers 5 are mounted
on the bolts 4 between the bars, the forward
ends of the bars diverge forwardly in be-
tween and in juxtaposition to the bars 1.

The bars 1 are pivotally connected to the 65
vertical flanges 6 of the bars 3 at points
removed from the forward ends of the latter
by bolts 7, said bars 1 being arranged be-
neath the horizontal flanges 8 and spaced
from the flanges 6 by washers 9. 70

The bars 1 and 3 are connected by ad-
justable cushioning means, each of which
consists of a hook rod 10, the shank of which
extends vertically through the flange 8 be-
tween the flange 6 and the bar 1, while the 75
hook 11 carried by the lower end engages
and receives the bar 1. A nut 12 is mounted
on the upper end of the hook rod and pro-
vides means for varying the tension of a
cushion spring 13 carried by the rod. 80

A seat 14 is detachably connected to the
rear end of the bars 3 by a bolt and clamp 15.

In practice the front ends of the bars 1
are connected to some intermediate part of
the machine or its frame so that the rear 85
ends of the bars 1 rest on the rear of the
machine frame. When so attached and posi-
tioned it will be noted that the bars 3 can
freely rock on their pivots under the weight
of a person in the seat against the tension of 90
the cushion springs. The tension of the
cushion springs can be readily varied to
compensate for persons of varying weight,
by adjusting the nuts 12.

Having described my invention, what I 95
claim as new, is:

A seat attachment comprising a pair of
spaced bars, another pair of bars pivoted at
points removed from their forward ends to
said first bars, a hook rod having its shank 100
extending through each of the forward ends
of said second bars and its lower hook end

engaging the adjacent first bar, an adjusting nut carried by the upper end of each hook rod, a cushion spring on each hook rod between said adjusting nut and second bar, and 5 a seat carried by the rear ends of said second bars.

In testimony whereof I have signed my

name to this specification in the presence of two subscribing witnesses.

JOHN P. KYLE.

Witnesses:

W. PELL,

L. M. BUCKMASTER.
